UNITED STATES PATENT OFFICE.

ALFRED INGRAM AND HARRY INGRAM, OF BROOKLYN, NEW YORK, ASSIGNEES TO INGRAMS INCORPORATED, OF BROOKLYN, NEW YORK, A CORPORATION OF NEW YORK.

CLOSURE FOR JARS, BOTTLES, AND OTHER RECEPTACLES.

1,386,624.

Specification of Letters Patent. Patented Aug. 9, 1921.

Application filed October 5, 1917. Serial No. 194,839.

To all whom it may concern:

Be it known that we, ALFRED INGRAM and HARRY INGRAM, citizens of the United States, and residents of Brooklyn, in the county of Kings and State of New York, have invented certain new and useful Improvements in Closures for Jars, Bottles, and other Receptacles, of which the following is a specification.

10 The invention resides more particularly in a cap of tin or other suitable metal, with a special compressible gasket in the flange or skirt portion thereof, adapted to the effectual sealing of glass tumblers, jars and other containers, said cap being constructed to be held on the container by the compression of the gasket against the exterior surfaces of the container and the frictional engagement of portions of the said flange or 20 skirt with said exterior surfaces. One purpose of the invention is to provide a cap and gasket readily capable of being effectually sealed against plain exterior surfaces of a container, such as a glass tumbler, even though said surfaces may be tapered as distinguished from being vertical.

In carrying out our invention we provide a metal cap adapted to pass downwardly over the upper end of a container 30 and having a depending flange or skirt portion which is specially shaped, beaded or grooved to receive a packing ring or gasket initially not conforming to the shape of the groove but to be deformed and compressed 35 therein upon and during the application of the cap to the container, and in accordance with our invention the flange or skirt portion of the cap is of such construction that upon the application of the cap and gasket 40 to the container, the gasket may effect the sealing and said flange or skirt portion firmly and frictionally engage the exterior surface of the container below said gasket.

We provide two means for securing the cap 45 upon the container, one being the compressibility of the gasket and the other the features of the flange or skirt portion of the cap below the gasket for engaging the exterior surfaces of the container, and these 50 two means coöperate, with the gasket affording an important auxiliary to the other means to prevent accidental displacement of the cap under variations in the exterior surfaces of the container.

55 The invention will be fully understood from the detailed description hereinafter

presented, reference being had to the accompanying drawings, in which:

Figure 1 is a side elevation, partly in section, of a container, with the cap or closure 60 of our invention superposed over the same and ready to be applied thereto, said closure being shown in central vertical section;

Fig. 2 is a central vertical section through the upper portion of a container and the 65 closure of our invention, said closure being shown as having been pressed downwardly upon and sealing the container, and the gasket being shown as having been deformed by its engagement with the exterior 70 surfaces of the container;

Fig. 3 is a side elevation, on a smaller scale, of the upper portion of a container sealed with the closure of our invention;

Fig. 4 is a like view showing a modification 75 in the construction of the flange or skirt portion of the cap;

Fig. 5 is a vertical section on a larger scale, through a portion of the same, taken on the dotted line 5—5 of Fig. 4; 80

Fig. 6 is a view corresponding with Fig. 4, but indicating a further modified construction of the flange or skirt portion of the cap, and

Fig. 7 is a vertical section, on a larger 85 scale, through the same, taken on the dotted line 7—7 of Fig. 6.

In the drawings, referring to Figs. 1, 2 and 3, 10 designates a container, which may be a glass tumbler, 11 the contents thereof, 90 12 the cap, 13 a downwardly depending flange or skirt constituting a portion of said cap, 14 an annular inwardly beaded or grooved section of said flange or skirt whose inner convex portion is adapted to engage 95 the exterior surface of the container, 15 an upper outwardly beaded or grooved section of said flange or skirt, and 16 a gasket of any suitable compressible material adapted to said section 15 and normally extending 100 inwardly on a circle less in diameter than the exterior diameter of the upper end of the container, so that upon the application of the cap to the container the container acting against said gasket may compress the 105 same within said section 15 and cause said gasket in compressed condition to closely bind against the upper exterior surface of the container. The beaded section 15 stands outwardly beyond the vertical plane of the 110 sides of the tumbler 10 and curves downwardly and outwardly from the flat top of

the cap 12, commencing outwardly from the lip around the mouth of the tumbler, and then curves inwardly and merges into the inwardly and then outwardly curved or 5 beaded gripping section 14 of the skirt 13.

The annular inwardly beaded section 14 of the flange or skirt of the cap will normally be slightly less in horizontal diameter than the external diameter of the upper 10 edge of the container 10, so that upon the application of the cap to the container, said section 14 will be forced outwardly to a limited extent and by the resiliency of the metal cling against the exterior surface of 15 the container, so as to afford a frictional or binding engagement of the flange or skirt 13 against said container. We preferably form the upper exterior portions of the container with vertical sides 17 so as to assure 20 the firm engagement of the beaded section 14 of the cap with said container when the cap is in position thereupon. The engagement of the beaded section 14 with the container does not prove entirely effectual for 25 sealing the container, because in many instances containers although intended to be accurate are irregular or tapered around their upper portions and in addition the upper edges of glass containers have certain 30 irregularities and very fine grooves due to natural conditions in the production of the containers, and these irregularities and fine grooves, sometimes hardly perceptible to the eye, prevent a metal cap alone from 35 sealing in an air-tight manner the container. In accordance with our invention we rely for the sealing of the container, on the outwardly beaded section 15 of the cap and the gasket 16 therein to be compressed against 40 the exterior surfaces of the container adjacent to the upper edges thereof, where irregularities and fine grooves are present in many glass containers as at present manufactured. The beaded section 15 extends 45 outwardly beyond the inwardly beaded section 14, and within said beaded section 15 we apply the gasket 16 which normally, as shown in Fig. 1, does not completely fill the groove within said section 15, but stands 50 therein at an angle and has parallel flat inner and outer surfaces, a flat upper edge and a tapered lower edge 18 which normally projects inwardly on a diameter which is less than the external diameter of the upper 55 end of the container 10, so that upon the application of the cap and gasket to the container, the upper outer edge portions of the container will engage said tapered edge 18 of the gasket and force said gasket outwardly, with compressible effect, into the 60 groove of the beaded section 15 of the cap, the result being that as the cap is continued on its downward movement upon the container, the gasket 16 becomes greatly deformed and compressed and fills the groove 65

of the beaded section 15 of the cap and very firmly engages the exterior surfaces of the upper edge portions of the container 10, as shown in Fig. 2. The gasket 16 when transformed from the condition in which it is 70 shown in Fig. 1 to that in which it is presented in Fig. 2, firmly binds against the exterior upper edge portions of the container and effectually seals the container notwithstanding such irregularities, fine recesses and grooves as may be created therein during the manufacture of the container. The gasket 16 normally does not fit the groove of the beaded section 15 of the cap, but is placed at an angle therein so that 80 quite a substantial portion of the gasket stands inwardly beyond the outer upper edges of the container, and due to this the application of the cap to the container results in the gasket being deformed outwardly to fill the groove in the section 15 of the cap and to be compressed along an adequate surface against the exterior upper edges of the container. The downward and outward beveling of the lower edge of the 85 gasket 16, as at 18, assures the proper outward compression of the gasket into the section 15 of the cap, so that the gasket does not become pressed upwardly against the top of the cap and over the upper edge of 90 the container, but outwardly into the beaded section 15 and against the exterior upper surfaces of the container. The compression of the gasket 16 against the upper exterior surfaces of the container not only adapts 95 the cap for containers which vary in their upper edge portions, but coacts with the inwardly beaded section 14 in locking the cap upon the container. Our purpose is to secure an effectual seal so that the contents 100 of the container may be preserved, and this result may be accomplished with entire satisfaction with the presence of the gasket 16 within the upper beaded section 15 of the cap, and we believe said result cannot be 105 accomplished in any satisfactory or universal manner with simply the engagement of the inwardly beaded section 14 with the exterior surfaces of the container. We prefer that the upper outer portions of the container 10 have vertical surfaces 17, below 110 which the container may be tapered, but we are aware that the difficulties of manufacturing the containers at reasonable expense and with the ordinary appliances frequently 115 result in the section 17 not being truly vertical, but somewhat tapered, and in all such instances the seal of the cap upon the container cannot be effectual with the inwardly beaded section 14, but is effectual when said 120 section 14 is supplemented with the beaded section 17 containing the gasket 16, especially when said gasket normally is of less diameter than the outer diameter of the 125 upper end of the container. 130

In Figs. 4 and 5 we illustrate a modification of our invention in which we number the container 19, the cap 20 and the skirt portion of the cap 21. The container 19 corresponds with the container 10 of Figs. 1 and 2, and the cap 20 is of tin or other suitable metal and formed at its outer peripheral edges within the flange or skirt 21 with a groove or beaded section 22, which 10 is somewhat more extended in dimensions than the beaded section 15 of Figs. 1 and 2. The lower portions of the flange or skirt 21 are inclined inwardly, as at 23, and then flanged downwardly, as at 24, the body of 15 the flange 24 being normally free of the exterior surface of the container 19, but having spring lips 25 slit and pressed inwardly therefrom so as to engage and bind against the exterior surfaces of the container 19. 20 when the cap 20 is pressed downwardly thereupon, said lips 25 then serving to aid in locking the cap upon the container. Within the grooved section or beading 22 of the cap 20, we place a gasket 26 which 25 although larger is normally of the same shape as the gasket 16 and then has a beveled lower edge corresponding with the edge 18 in Fig. 1 and normally on a smaller diameter than the exterior diameter of the 30 upper edge of the container 19, so that upon the application of the cap to the container, said beveled lower edge of the gasket will be engaged by the upper edge of the container and the container, as the cap is forced 35 downwardly thereupon will compress the gasket outwardly into the section 22 of the cap and effect the close binding of the gasket 26 against the inner surfaces of said section 22 and against the upper outer surfaces 40 of the container 19, the result being the effectual hermetic sealing of the container. In the construction shown in Figs. 4 and 5 the gasket seals the upper end of the container regardless of the usual irregularities 45 that are present in glass containers and in addition by its binding force against the container serves to aid in locking the cap 20 in position and to coöperate, in locking said cap, with the frictional engagement 50 of the lips 25 with the exterior surfaces of the container.

In Figs. 6 and 7 we illustrate a further modification of the invention, and in Figs. 6 and 7 the container is numbered 27, the cap 28 and the gasket 29. The cap 28 has a flange or skirt portion 30 which differs from the flange or skirt portion 21 of Figs. 4 and 5, merely in the fact that in lieu of forming in the lower flange portion thereof 60 the spring lips 25 of Figs. 4 and 5, we merely indent said flange portion, as at 81, to form inwardly projecting lugs to frictionally engage the exterior surface of the container 27 when the cap 28 is pressed 65 downwardly thereupon. The gasket 29 of

Figs. 6 and 7 is the same as the gasket of Figs. 4 and 5, and in view of the small difference between the structures shown in Figs. 4, 5 and 6, 7, it is thought that extended explanation as to the modification 70 presented in Figs. 6 and 7 will not be required.

In all of the constructions shown we employ a cap having a flange or skirt portion possessing in a part thereof, means for 75 resiliently engaging the exterior surface of the container, and in each instance the flange has an upper peripheral outwardly beaded section containing a gasket which normally, at its lower edges, is less in diameter than the diameter of the upper outer edges of the container, so that upon the application of the closure to the container the gasket is compressed outwardly to fill 80 said beaded section and also becomes very 85 firmly bound against the upper exterior edge portions of the container, said gasket thus not only creating an effectual outer seal, but coöperating with the lower or resilient portions of the flange in locking 90 the cap on the container. In all the constructions shown the container has about its upper end the usual smooth plain substantially vertical exterior surfaces commonly possessed by tumblers employed for 95 holding food products, and in all said constructions the upper end of the tumbler passes through the gasket, with the result that the cap seats on the upper edge of the tumbler and the gasket affords an efficient side-seal, while at the same time aiding materially in securing the cap on the tumbler. 100

What we claim as our invention and desire to secure by Letters Patent, is:

1. A container having substantially vertical smooth exterior rigid side surfaces about its upper end, and a closure therefor and constructed with relation thereto, comprising 105 a cap having a top and a depending annular flange adapted to fit over the container and in one transverse section having an inwardly curved resilient portion defining a diameter less than that of the container and adapted to firmly grip the smooth side surfaces thereof, and a ring gasket within the upper outer edges of said cap to engage with sealing effect the upper side surfaces of the container above said gripping portion of 110 said flange, said cap at its upper outer edges beyond the vertical plane of the sides of the container being annularly outwardly and then inwardly curved to form an annular recess to receive said gasket and afford a supporting shoulder therefor at the lower 115 edge thereof, and said gasket in its initial position being supported at an angle on said shoulder and not filling said recess and with one annular portion standing within the vertical plane of the upper outer edges of the 120

125

130

1 container so that when a cap is applied to position on the container its top will seat on the upper edge thereof, the upper end of the container will pass through the gasket and 5 said gasket will be deformed laterally to fill said recess and firmly bind against the exterior side surfaces of the container below the lip thereof, and said gasket then affording an efficient side seal and at the same time co- 10 operating with the inwardly curved gripping portion of the aforesaid flange below the same in securing the cap on the container.

2. A container having substantially vertical smooth exterior rigid side surfaces about 15 its upper end, and a closure therefor and constructed with relation thereto, comprising a cap having a top and a depending annular flange adapted to fit over the container and in one transverse section having an inwardly set resilient portion defining a diameter less than that of the container and adapted to firmly grip the smooth side surfaces thereof, and a ring gasket within the 20 upper outer edges of said cap to engage with sealing effect the upper side surfaces of the container above said gripping portion of said flange, said cap at its upper outer edges outwardly beyond the vertical 25 plane of the sides of the container being annularly outwardly beaded to form an annular recess exterior to the sides of the container to receive said gasket and afford a supporting shoulder therefor at the lower 30 edge thereof, and said gasket initially not filling said recess and having a downwardly and outwardly beveled lower edge whose inner portions in the initial position of the gasket in the cap, are normally less in diameter than the upper end of said container 35 so that when the cap is applied to position on the container its top will seat on the upper edge thereof, the upper end of the container will pass through the gasket and said 40 gasket will be deformed to fill said recess and firmly bind against the exterior side surfaces of the container below the lip thereof, and said gasket then affording an efficient side seal and at the same time co-operating 45 with the inwardly set portion of the aforesaid flange below the same in securing the cap on the container.

3. A container having substantially vertical smooth exterior rigid side surfaces about 55 its upper end, and a closure therefor and constructed with relation thereto, comprising a cap having a top and a depending annular flange adapted to fit over the container and in one transverse section having an inwardly set 60 deformable resilient beaded portion defining a diameter less than that of the container and adapted to annularly firmly grip the smooth side surfaces thereof, and a ring gasket within the upper outer edges of said 65 cap to engage with sealing effect the upper

side surfaces of the container above said gripping portion of said flange, said cap at its upper outer edges beyond the plane of the sides of the container being annularly outwardly beaded to form an annular recess to receive said gasket and afford a supporting shoulder therefor at the lower edge thereof, and said gasket in its initial position being supported at an angle on said shoulder and not filling said recess and with one annular 70 portion standing within the vertical plane of the upper outer edges of the container so that when the cap is applied to position on the container its top will seat on the upper edge thereof, the upper end of the container will 75 pass through the gasket and said gasket will be deformed to fill said recess and firmly bind against the exterior side surfaces of the container below the lip thereof, and said gasket then affording an efficient side seal 80 and at the same time co-operating with the inwardly set portion of the aforesaid flange below the same in securing the cap on the container.

4. A container having substantially vertical smooth exterior rigid side surfaces about 85 its upper end, and a closure therefor and constructed with relation thereto, comprising a cap having a top and a depending annular flange adapted to fit over the container and 90 having a lower resilient portion integrally formed with inwardly set portions defining a diameter less than that of the container and adapted to firmly grip the smooth side surfaces thereof, and a ring gasket within 95 the upper outer edges of said cap to engage with sealing effect the upper side surfaces of the container above said gripping portion of said flange, said cap at its upper outer edges outwardly beyond the vertical plane of the 100 sides of the container being formed with an annular recess to receive said gasket and afford a shoulder below the same and said gasket in its initial position being supported 105 at an angle on said shoulder and not filling 110 said recess and with one annular portion standing within the vertical plane of the upper outer edges of the container so that when the cap is applied to position on the container the upper end of the container will deform said gasket laterally to fill said recess and cause the same to bind against the side of the container below the lip thereof with sealing effect, said gasket then co-operating 115 with said inwardly set portion to effectually seal the container and secure the cap thereon.

Signed at New York city, in the county of New York and State of New York, this 27th day of September A. D. 1917.
